MOSES E. CHENEY, OF LA CROSSE, WISCONSIN, ASSIGNOR, BY MESNE ASSIGNMENTS, TO MCTO METER GAUGE & EQUIPMENT CORPORATION, OF LONG ISLAND CITY, NEW YORK, A CORPORATION OF DELAWARE

THERMOMETER BULB

Application filed March 24, 1928. Serial No. 264,499.

This invention relates to an improvement in the manufacture of thermometers and more particularly to an improved method of attaching one end of a capillary tube to a thermometer bulb of the metallic type. Under certain conditions a thermometer bulb of this type is subjected to severe mechanical strains and high pressures, for example, in the water jacket of a gasoline engine where there is considerable vibration, excessive heat, and high pressures at different times, and in the handling of same.

In prior constructions considerable difficulty was experienced in sealing the metallic bulb and capillary tube together in such a manner as to withstand the shocks and strains to which it is often subjected.

Solder has often been used for securing the parts together but it requires some expert skill to obtain an absolutely tight connection.

Attempts have been made to remedy this difficulty by first soldering to the open end of the bulb a separate piece of metal in order to produce a proper bearing surface for the capillary tube but a much larger area was thereby required to be soldered, the chances of producing a fluid tight joint being greatly reduced and the expense somewhat increased.

The capillary tube in this type of thermometer has heretofore never been properly protected against accidental bends and sharp turns. Unless great care was used in bending the tube into the desired curve, a severe fracture resulted, that is the tubing was very apt to become "kinked" rendering the instrument useless.

One part of my invention is a method of making a metallic bulb from a single sheet of metal and by a series of drawing, punching and spinning operations work it into a tube having both ends closed except a small opening in one end just large enough for the insertion of a capillary tube.

Another object of my invention is to provide a metallic thermometer bulb with a reduced portion intermediate its ends leaving an open ended part adjacent said reduced portion forming a cup shaped receptacle for

the insertion of flexible protecting means for the capillary tube, preferably an armored tube.

Another object is to provide a one piece thermometer bulb with a cup shaped portion for the reception of one end of the protecting means, a reduced neck portion for supporting a capillary tube, and an enlarged bulb portion having both ends closed except for the opening in said reduced portion.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is an assembly view of the thermometer bulb showing the capillary tube and protecting means in place. Fig. 2 shows the bulb at an early stage in formation. Fig. 3 is a view of the bulb in one of its intermediate stages of completion. Fig. 4 shows the bulb in one stage of an alternative method of forming the reduced neck portion.

Referring to Fig. 1 the bulb 10 is preferably made of copper or other conveniently worked metal and by a series of operations such as punching, drawing and spinning the original piece of metal is formed into the shape shown. Fig. 2 shows the bulb appearing as a tube having one end closed, this represents a step in the early stages of development. From this stage to the completed bulb various methods of forming the reduced portion and cup portion may be employed but I have found it preferable to first form a flange 11 near the open end of the bulb and then the reduced portion 12. The flange 11 forms an annular collar whereby the bulb may be securely held in a fitting suitably threaded into the water jacket of a water cooled engine as shown in my co-pending application filed March 1, 1928, Serial No. 100

258,290. The portion of the bulb 10 which projects within the water jacket extends below the flange 11 (Fig. 1) and this becomes in effect a closed chamber when the capillary is inserted within the bulb as hereinafter more fully described.

The groove or neck portion is then formed by suitable grooving wheels to the desired diameter. This completes the process of 10 forming the bulb and the result is a one piece bulb formed in a way to be free from solder or leaky joints.

Obviously any other sequence of operations may be followed as for example the neck portion 13 may be formed before reducing the cup portion 12 to the desired size as shown in Fig. 4.

The capillary tube 14 is inserted into the opening 15 formed by the neck portion 13 20 and soldered at 16. Thus it will be seen that only a very small amount of solder is required to securely hold the tube 14 in place since the inner walls of neck 13 assist in rigidly holding the tube in place.

25 25 In order to protect the capillary tube 14 against short bends and other fractures I preferably employ a coiled spring 17 of slightly larger diameter than the capillary tube in order that any relative longitudinal 30 movement between the tube 14 and coil 17 may easily take place. One end of the coil 17 is securely fastened within the cup shaped opening 12 of the bulb 10 by crimping the portion 12 into close contact with the coil. 35 Any other method of holding the coil within the socket 12 may be employed as for example, shallow screw threads may be formed on the inner surface of the cup and the coil may be screwed into place. However for 40 convenience in manufacture and to save expense the coil is held within the cup in the manner previously described.

The other end of the coil is left unfastened to permit relative movement between the coil 45 and the tube when it is bent or curved in any position desired, and as illustrated in Figure 1 the parts are so proportioned that the receptacle 12 contains a number of coils of the protective tube.

50 50 Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equiva-

lents thereof, by Letters Patent of United States:—

1. As an article of manufacture a thermometer bulb comprising a metallic body portion having a socket shaped opening at 70 one end, a reduced portion between said socket portion and body portion, a capillary tube one end of which is inserted within said body and extending through said reduced portion and is soldered thereto, a flexible protecting device surrounding said capillary tube, and means to secure one end of said device within said cup shaped opening.

2. In an instrument of the character described, a metallic thermometer bulb having one end formed with a reduced neck portion, with enlarged portions above and below said neck portion; there being an opening through said neck portion, a capillary tube 85 extending through said opening and supported by the walls thereof and being soldered thereto, the solder being placed in the pocket formed by the inner wall of the outer enlarged portion and said capillary. 90

3. A device of the character described comprising a metallic thermometer bulb grooved at one end to form a reduced neck portion and a socket portion, a capillary extending through said neck portion and soldered thereto, a coiled spring surrounding said capillary to protect the same against crushing or being kinked and means to hold 95 said spring within said socket portion. 95

4. A device of the character described comprising an open ended thermometer bulb grooved at said end to form a ferrule projecting from said groove, a capillary tube inserted within said bulb and fitting within the grooved portion and extending through 100 said ferrule, a guard for said tube, said guard being securely held within said ferrule by crimping the latter against the former. 100

5. As an article of manufacture a thermometer bulb comprising a one piece metallic structure having a bulb portion closed at its lower end, an intermediate neck portion of a size to contain and support a capillary tube, 110 a cup-shaped part adjacent the neck portion, and an armored guard member supported in said cup-shaped part. 115

6. In an instrument of the character specified the combination of a capillary tube with a unitary metallic bulb structure comprising the lower bulb portion, an intermediate neck portion and an upper enlarged portion, the capillary tube being inserted through said neck portion, the latter having its inner surface inclined away from the capillary tube to form a pocket for solder whereby the tube will be securely held. 120

7. In an instrument of the character specified the combination of a capillary tube with a metallic bulb structure having a re- 130

duced neck portion with curved inner walls for receiving and centering the capillary tube, said walls inclining away from the tube to form an open pocket and a guard member supported in the latter.

5 In witness whereof, I hereunto subscribe my name.

MOSES E. CHENEY.
